UNITED STATES PATENT OFFICE

EDELBERT JOHN KNAPP, OF NORTON, KANSAS

LUBRICATED ROCKER ARM

Application filed November 12, 1931. Serial No. 574,657.

My invention relates to rocker arms and particularly to rocker arms having means for lubricating all of the bearings of the rocker arm. One object of the invention is the provision of a rocker arm having an upper surface so designed that the movements of the rocker arm will carry the lubricant to all of the bearings.

Another object of the invention is the provision of means actuated by the rocker arm for elevating the lubricant to be discharged on the upper surface of the rocker arm.

It is also my object to provide a novel form of mechanism for lifting the lubricant from the lubricant receptacle to the upper surface of the rocker arm.

Having in view these objects and others which will be pointed out in the following description, I will now refer to the drawing, in which

Figure 1 is a view in perspective showing the rocker arm with its lubricant channels and showing also the mechanism for lifting the lubricant to the upper surface of the rocker arm.

Figure 2 is a view in vertical section of the lubricant lifting mechanism, a fragment of the rocker arm being also shown in section.

The rocker arm 10 has two shafts 11 and 12. In my construction the shaft 11 is the fixed shaft about which the rocker arm oscillates while the shaft 12 is at the free end of the rocker arm to move up and down during the oscillations of the rocker arm. As far as the present construction is concerned, however, the arrangement may be reversed so that the rocker arm will oscillate about a fixed axis of the shaft 12.

Intermediate the shafts 11 and 12 is a depression 13 bounded by the raised walls 14 of the rocker arm and by a closed wall 15 surrounding the aperture 16. This depression 13 communicates with the channels 17 leading to the bearings of the shaft 11 and with the channels 18 leading to the bearings of the shaft 12. It is obvious that any lubricant in the depression 13 will be rocked back and forth so as to alternately carry it through the channels 17 and 18.

The rocker arm is positioned at some dis-

tance above an oil bath such as shown at 19. A conduit 20 is seated within this oil bath and a second conduit 21 is positioned in the conduit 20 to slide up and down therein. The conduit 21 is provided with a head 22 which normally rests on the upper surface of the flange 15. It is obvious that the rocking movements of the rocker arm will cause the head 22 to rise and fall carrying with it the entire conduit 21. The conduits 20 and 21 are provided with apertures 23 and 24 in their lower ends and these apertures are controlled through ball valves 25 and 26 respectively. It will be apparent that when the conduit 21 moves downwardly the aperture 24 will be open but the aperture 23 will be closed by the ball valve 25 due to the downward pressure within the conduit 20. On the other hand, when the conduit 21 is moving upwardly the aperture 23 will be open but the aperture 24 will be closed due to the weight of the lubricant within the conduit 20. The reciprocation of the conduit 21 will therefore cause the movement of the lubricant upward in that conduit to be discharged over the upper surface of the head 22 into the depression 13 where it will be carried to all of the bearings of the rocker arm during the rocking movements of the rocker arm.

The operation depends, of course, very largely on the weight and the viscosity of the lubricant. This lubricant has a normal level in the oil bath as shown in Figure 2 and it tends to maintain the same level in the cylinder 20 and in the piston 21. The only factor to disturb this tendency is the use of the two ball valves 25 and 26. The cylinder 20 has a loose relation at its point of suspension as shown in Figure 2 and the piston 21 has a loose sliding relation within the cylinder 20. In the former of these two the oil level can not be disturbed by the piston 21 since the loose relation permits the admission of the air to the surface of the body of oil in the oil bath to provide the necessary atmospheric pressure for the proper operation of my device. The space between the piston 21 and the cylinder 20 readily becomes filled with oil having the necessary viscosity. Even though some oil might be discharged over

the top edge of the cylinder 20, that oil would drain back into the oil bath but it would not disturb the operation of the pump as a whole.

On the downward stroke of the piston 21, the valve 26 is open but the valve 25 is closed. The downward movement of the piston is rather slow because it is carried downwardly under its own weight alone into a viscous mass of oil. The oil level within the piston 10 rises and then on the upward stroke, which is the power stroke for the piston, the oil is carried upwardly with the piston so that on the next downward stroke a few drops of the oil will be caused to ooze out through the 15 mouth of the piston 21 and over the convex surface of the head 22. The quantity of oil thus oozing out is very small but only an exceedingly small quantity is required for lubricating the bearings of the rocker arm.

My rocker arm with its lubrication system should not be confused with those rocker arms which either operate entirely within the lubricant or which dip into the lubricant during the rocking movements. My rocker arm is positioned entirely above the lubricant where it does not come into direct contact with the lubricating material in the oil bath. This material must be elevated to 20 reach the rocker arm and for this purpose I employ the pumping device as above described. The lubricant is thus carried slowly and steadily to the surface of the head 22 from which it flows down into the depressed portion 13 of the rocker arm. It should also be noted that this depressed portion is between the two ends of the rocker arm rather than at one end thereof. The result is that 25 the motion of the rocker arm in one direction carries the lubricant from the depressed portion 13 to one pair of bearings while movement of the rocker arm in the other direction carries the lubricant to the other bearings. If an excess of lubricant is carried to the bearings, the surplus will drip back directly into 30 the oil bath.

The path of the free extremity of the rocker arm is not in a straight line but it is rather in the form of an arc. To some extent this would affect the movement of the conduit 21 35 although the size of the opening 16 is such as to permit vertical movement of the conduit 21 even though the free end of the rocker arm has an arcuate path. In machines of this type, however, the vibration is often such 40 that the conduit 21 can not always move in a straight line. For this reason the conduit 20 is suspended as shown in Figure 2 so that it is permitted to rock. The conduit 21 of course will partake of the same rocking movements which will not interfere with the sliding movements of the conduit 21.

Having thus described my invention in such full, clear, and exact terms that its construction and operation will be readily understood by others skilled in the art to which

it pertains, what I claim as new and desire to secure by Letters Patent of the United States is:

1. A rocker arm positioned above an oil bath and out of direct contact therewith, fixed and movable bearings at opposite extremities of said rocker arm, the free extremity of said rocker arm describing an arcuate path intersecting a horizontal line through said fixed bearing, said rocker arm being provided with an aperture intermediate its extremities, means for conducting lubricant to the upper surface of said rocker arm at a point intermediate the extremities thereof, said means including a tubular member loosely suspended within the oil bath and having its upper portion extending above the surface of the oil, a hollow piston slidable in said tubular member and projecting through the aperture in said rocker arm, said tubular member and said hollow piston being each provided with valves for retarding the reverse flow of oil therein, a head on said hollow piston whereby the rocking of said rocker arm is communicated to said hollow piston to force oil therethrough and onto the surface of said rocker arm, and channels for conducting the lubricant alternately to the bearings at the opposite extremities of said rocker arm during the rocking movements thereof.

2. A rocker arm positioned above an oil bath and out of direct contact therewith, said rocker arm being provided with a vertical aperture intermediate the extremities thereof, a hollow piston having free sliding movement through the aperture of said rocker arm, said piston terminating at its upper extremity in a head adapted to rest against the upper surface of said rocker arm surrounding the aperture thereof, said head having a convex upper surface, a cylinder loosely suspended with its lower portion within the oil bath, and valves in the lower extremities of said hollow piston and said cylinder, the arrangement being such that the oil oozes out through the top of said hollow piston and over the convex surface of said head when said piston is carried downwardly by its weight and the weight of the oil contained therein.

In testimony whereof I affix my signature.
EDELBERT JOHN KNAPP.
